Specification for Design.

Patented Aug. 15, 1922.

Application filed November 12, 1920. Serial No. 423,735. Term of patent 3½ years.

To all whom it may concern:

Be it known that I, CHARLES B. NAMIOT, a citizen of the United States, residing at New York city, in the county of Bronx and State of New York, have invented a new, original, and ornamental Design for Wedding Rings, of which the following is a specification, reference being had to the accompanying drawing, forming part thereof, in which—

Fig. 1 is a perspective view of a wedding ring showing my new design,
Fig. 2 is an edge view thereof.

I claim:

The ornamental design for a wedding ring as shown.

CHARLES B. NAMIOT.
